(57) **CLAIM**

The ornamental design for an vehicle rear reflector, as shown and described.

DESCRIPTION

FIG. 1 is a front perspective view of an vehicle rear reflector according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines illustrate portions of the vehicle rear reflector that form no part of the claimed design.

Areas of the design shown with a stipple fill shading are to indicate a contrasting appearance.

1 Claim, 4 Drawing Sheets
